UNITED STATES PATENT OFFICE.

HOMER B. SPRAGUE, OF BOSTON, MASSACHUSETTS.

WINDMILL.

SPECIFICATION forming part of Letters Patent No. 273,182, dated February 27, 1883.

Application filed December 11, 1882. (No model.)

To all whom it may concern:

Be it known that I, HOMER B. SPRAGUE, a citizen of the United States, residing at Boston, in the county of Suffolk and State of Massachusetts, have invented certain new and useful Improvements in Windmills; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to an improvement in that class of windmills in which the sails or vanes automatically adjust themselves to the varying force of the wind, with especial reference to Patent No. 243,169, granted to me June 21, 1881; and the invention consists in certain details of construction hereinafter particularly set forth.

Referring to the accompanying drawings, Figure 1 is a front view of a windmill embodying my invention. Fig. 2 is a vertical section of the same. Figs. 3 to 8 are enlarged views in detail of several features of the windmill.

A is a hollow iron standard, secured to a floor or other suitable support, A'.

B is a frame provided at the bottom with a pipe, which fits into and extends downward a short distance in the standard A, so as to turn freely in the same.

Supported in suitable bearings in the frame B is a hollow axle, C, having at its front end a hub, D, to which are attached the radial arms or spokes E. The outer ends of the arms E are provided with small cast-metal caps F, each having a pin or stud, f. (Shown enlarged in Fig. 4.) A flat strip of metal or rim, G, about one inch in width, (more or less,) provided with holes, is then placed around the ends of the arms E, the holes fitting over the pins f. The two ends of the metal strip G are placed upon the same pin, which is then riveted, and the strip is thus secured firmly in position. The radial arms E are set at an angle with the axis, so as to incline inwardly or to the rear, as shown, by which means greater strength to resist the wind is obtained.

The arms E are made of wedge shape in cross-section, so as to present the sharp edge to the wind, and thus cause less resistance.

The sails or canvas H are attached to frames H', of light steel wire, as shown in Fig. 3, provided with eyes a b. The frames are attached to the arms E by screwed eyebolts, one of which passes through the eye a, by which the sail is prevented from shifting on the spokes or arms. To the eye b is attached a wire, cord, or chain, I, at the outer free ends of the sails, so as to hold the sails in their relative positions. To a long rod or wire, e, are attached, at its outer end, two short rods or wires, c d, the other end of rod c being attached to the eye b or any other part of the sail-frame, and the outer end of rod d being attached to the end of the arms E. The inner ends of the rods e are attached to chains g, which pass into the hollow axle C, where they are connected to a sliding swivel-frame, J, shown enlarged in Fig. 5, and consisting of a hollow cylinder fitted with a screw cap or cover, l, through which passes the shank of the hook m, provided on the inside of the screw-cap with a head or nut, n, so as to allow the cylinder to revolve around the shank of the hook m and not rotate the hook.

In order to prevent the cylinder or swivel J from rotating within the axis C, I attach to the said cylinder feathers p p, as shown in Fig. 5, which fit in grooves q q, Fig. 6, that extend the whole length of the axis. The chains g g, that pass through the hub D, are attached to a loop, r, at one end of the swivel-cylinder J, and to the hook m at the opposite end is attached a rope or chain, h, which passes over the pulleys i j, and has a weight, k, at the lower end. The cylinder J serves as an oil-reservoir for lubrication, the oil being inserted in an orifice closed by a screw, s.

The hub D may be provided with pulleys for the chains g g to pass over in entering the axle C, to lessen the friction.

An up-and-down motion is imparted to the rod M, which connects with the pump or other machinery to be operated, by means of an eccentric, K, on the axle C, working in a loop, L. (See Figs. 2 and 7.)

In the drawings I have shown four sets of chains g and rods c d e; but more or less may be employed, as desired.

Fig. 8 shows a modification of the arrangement of the wires c d e for operating the sails. In this case the sails are set at an angle by

means of springs *t*, attached to the outer free end of one sail and to the arm carrying the next sail, so that the spring will act constantly to draw up the sail to catch the wind, and the 5 rods *c* and *d* are placed on the opposite side, so that when the weight *k* is on the chain *h* the rods *c d e* will be regulated by means of the spring.

What I claim as my invention, and desire to 10 secure by Letters Patent, is—

1. The arms *E*, set at angle with the axis of the windmill and inclining to the rear, in combination with the rim *G* and caps *F*, as and for the purpose set forth.

15 2. In a windmill, the combination of the

canvas *H*, the wire frame *H'*, provided with the eyes *a b*, the cord *I*, and arms *E*, substantially as and for the purpose set forth.

3. The sliding swivel *J*, provided with the feathers *p p*, in combination with the grooved 20 hollow axle *C*, as and for the purpose specified.

4. The combination, with the sails *H H'*, of the rods *c d e*, chain *g*, and sliding swivel *J*, substantially as and for the purpose set forth.

In testimony whereof I affix my signature in 25 presence of two witnesses.

HOMER B. SPRAGUE.
